UNITED STATES PATENT OFFICE

PAUL O. FARNHAM AND RAYMOND ASSERSON, OF BOONTON, NEW JERSEY, ASSIGNORS
TO RADIO FREQUENCY LABORATORIES, INCORPORATED, OF BOONTON, NEW JERSEY,
A CORPORATION OF NEW JERSEY

ELECTRICAL AMPLIFIER CIRCUIT

Application filed June 8, 1929. Serial No. 369,286.

This invention relates to electrical amplifier circuits, and more particularly to circuits including elements for automatically varying the effective amplification at different frequencies.

In audion amplifiers of the type in which tuning is effected by varying the capacity across a fixed inductance the gain is not uniform over a band of frequencies but increases progressively with increasing frequency. Although high amplification is usually desirable the substantial change in the amplification rate when the amplifier is to be tuned over a band of frequencies is objectionable, and particularly so in broadcast receivers and other cascaded amplifying systems. If a gain-wave length curve is plotted for the usual transformer coupled radio frequency amplifier stage, or for cascaded stages, the curve will have a relatively steep slope, the amplification at the higher frequencies within the broadcast range being approximately twice the amplification at the lower frequencies in the case of a triode and being several times as great in the case of a tetrode of the shield grid type.

An object of the present invention is to provide an electrical amplifier circuit in which the amplification rate may be approximately constant throughout a given range of frequencies. A further object is to provide an amplifier circuit in which the effective amplification is decreased, over a predetermined portion of the range of frequencies to which the amplifier may be tuned, by the radio frequency voltage drop established across a portion of the input circuit by amplified signal energy flowing in the output circuit.

More particularly, an object of the invention is to provide an electrical amplifier circuit in which a radio frequency impedance is connected between the cathode and the junction of the input and output circuits, the impedance being so proportioned that it is resonant at a frequency at or near the lower limit of the band of frequencies which is to be amplified.

These and other objects of the invention will be apparent from the following descrip-

tion when taken with the accompanying drawings in which:

Fig. 1 is a circuit diagram of an amplifier stage embodying the invention;

Figs. 2 and 3 are circuit diagrams illustrating other embodiments of the invention; and

Fig. 4 illustrates typical gain-wave length characteristic curves which will be herein-after explained.

In Fig. 1, the invention is illustrated as embodied in a balanced radio frequency amplifier stage of the type described in the patent to Hull, No. 1,672,811, June 5, 1928. The tuned input circuit L_0C_0 is connected between the grid G and the point Y in the cathode circuit to which the lower terminal of the plate impedance L_1 is also connected. The tuned output circuit which feeds the succeeding stage comprises the serially connected coils L_2 , L_3 and condenser C_2 . The coils L_1 and L_2 constitute a coupling transformer, while the coil L_3 has zero or negligible coupling with the other coils, the balance condenser C_3 being connected between the grid G and the junction of the coils L_2 , L_3 .

When the circuit includes only the elements which have been described above, the amplification rate or stage gain is materially higher at the shorter wave lengths than at the longer wave lengths. The novel construction which modifies the stage gain comprises the impedance Z_5 which is serially connected between the cathode and the junction Y of the input and output circuits. The radio frequency by-pass condenser C is connected across the plate current supply B but it is to be noted that the condenser C does not by-pass impedance Z_5 .

The impedance Z_5 is so chosen that the radio frequency potential drop across the impedance is greater at the higher than at the lower frequencies. It will be apparent that, due to the potential drop across the impedance Z_5 , the effective signal voltage between grid and cathode will not be the voltage across the resonant input circuit L_0C_0 . The impedance Z_5 may of course be so chosen that the stage gain may be decreased over any desired portion of the range

of frequencies to which the stage may be tuned.

One particular embodiment of the circuit for use with an alternating current tube of the UY-227 type is shown in Fig. 2. The general arrangement is the same as that shown in Fig. 1 but the sources of plate and cathode heating current are not shown. The low potential side of the input circuit is 10 grounded, as by connection to the shielding which is customarily employed, and the common portion of the input and output circuits lies between the ground or shield and the cathode.

15 This common portion of the cathode circuit includes the resistor R_c shunted by the composite impedance formed by inductance L_s in series with condenser C_s . The resistance R_c is the usual bias resistance and its 20 value is so chosen that the direct current potential drop across the resistance provides the negative bias for the grid. As usually employed, the bias resistance is shunted by a by-pass condenser of the order of one-half 25 m. f. which affords a path of negligible impedance for all frequencies within the range to be amplified.

In accordance with the present invention, 30 the usual by-pass condenser is replaced by the series resonant circuit $L_s C_s$ which corresponds to the generic impedance Z_s of Fig. 1, and the relative values of the impedances L_s and C_s are so chosen that the series circuit is resonant at or near the maximum wave 35 length to which the stage may be tuned.

The automatic gain control is equally applicable to amplifier stages embodying tetrodes of the shield grid type. The amplifier stage which is diagrammatically represented in Fig. 3 includes tuned input circuit $L_1 C_1$, a tuned output circuit $L_2 C_2$ and circuit connections for placing the desired positive potential upon the screen grid G_2 . Except for the provision of the impedance in that 40 portion of the cathode circuit which is common to the input and output circuits, the design and construction of the amplifier stage may be of any approved or desired form. The impedance is provided by the inductance 45 L_s in series with the condenser C_s which shunts the bias resistance R_c .

As applied to tetrodes, the present invention decreases the stage gain at short wave lengths without appreciable loss in selectivity, and therefore the construction is superior to those previously employed for securing an approximately uniform gain over the frequency range of an amplifier.

The curves of Fig. 4 are representations 60 of the gain-wave length characteristics of a conventional amplifier stage and amplifier stages embodying the invention. Curve A represents the performance of a balanced amplifier stage of the type shown in Fig. 2, but 65 in which the resistance R_c was shunted by a

1 m. f. condenser. It will be noted that the gain at 200 meters was approximately double the gain at 600 meters. Curves B and C represent the measured gain of the same stage when the usual by-pass condenser was replaced by the series resonant circuit $L_s C_s$. The coil L_s had an inductance of approximately 55 microhenries and the capacity of C_s was chosen for resonance of the impedance Z_s at 440 and 500 meters, respectively, that 75 is, curve B was obtained when C_s was .001 m. m. f. and curve C was obtained when C_s was .0014 m. m. f.

Attention is called to the fact that the gain is substantially unchanged for the frequencies at which the impedance Z_s is resonant and that the gain for lower frequencies is higher than the gain obtained when the bias resistance was shunted by the usual by-pass condenser. At frequencies above the resonant frequency of the impedance Z_s , the stage gain is substantially less than that of the usual circuit arrangement.

It will be apparent that the impedance Z_s may take the form of more or less complex impedances of a composite nature when it is desired to change the gain over a limited portion or portions of the wave-length range. In the design of broadcast receivers, however, the use of complex impedances is unnecessary, since the general flattening of the curve which may be obtained with a simple series circuit will usually meet the requirements when several stages are to be cascaded.

While the invention may be employed in amplifier stages of the conventional type as well as those which are balanced to prevent self-oscillation, it is particularly useful with such balanced stages, since the general balance conditions of the stage are not disturbed by the inclusion of the gain control impedance Z_s .

Although the invention has been specifically described in connection with stages designed for operation within the broadcast range, it will be apparent that the invention is applicable generally to all amplifier stages or cascaded stages. In an audio frequency amplifier stage, for example, the impedance Z_s may be so chosen as to effect a cutoff at or near a disturbing frequency.

The resonant impedance Z_s is effectively in shunt across the bias resistor R_c even when the inductance L_s is in series with the resistor since the direct current resistance of L_s is negligible.

We claim:

1. In an amplifier adapted to be tuned over a band of frequencies, the combination with an audion having a control electrode, a cathode and an anode, of an input circuit connected between control electrode and cathode, an output circuit connected between cathode and anode, and a circuit element constituting a series impedance common to both

said input and said output circuit, said circuit element being resonant at a frequency at the lower limit of the said band of frequencies.

5 2. In an amplifier adapted for operation over a band of frequencies, the combination with an audion having a control electrode, a cathode and an anode, an input circuit and an output circuit, of means for automatically decreasing the effective amplification over a portion of said band, said means comprising an impedance element connected between said cathode and the junction of said input and output circuits, the constants of said element being such that its impedance is greater at frequencies falling within said portion of the band than for frequencies lying outside of the same.

20 3. An audion amplifier of the type including an audion having an input and an output circuit, and a variable condenser for tuning one of said circuits over a band of frequencies, characterized by means for decreasing the variation of amplification with 25 changing wave length, said means including an impedance connected between said cathode and the junction of said input and output circuits, said impedance being reactive and having an impedance which, within the 30 frequency range of said amplifier, increases at a substantial rate with increasing frequencies.

4. In an audion amplifier, adapted to be tuned over a band of frequencies, the combination with an audion having a control electrode, a cathode and anode, an input circuit, and output circuit including a source of direct current, and a grid bias resistor in a common portion of said input and output 45 circuits, of an inductance and condenser forming a series resonant circuit effectively in shunt across said resistor, the values of the impedances in said series circuit being so related that the circuit is resonant at the lower end of said band of frequencies.

5. In an audion amplifier, adapted to be tuned over a band of frequencies, the combination with an audion having a control electrode, a cathode and anode, an input circuit, an output circuit including a source of direct current, a grid bias resistor in a common portion of said input and output circuits, and a condenser by-passing said resistor, of an inductance cooperating with said 55 condenser to form a resonant circuit in said common portion of said input and output circuits, the impedances of said inductance and condenser being so related that the circuit formed thereby is resonant at the lower 60 end of said band of frequencies.

In testimony whereof, we affix our signatures.

PAUL O. FARNHAM.
RAYMOND ASSERSON.
